Primary Examiner — Prabhakar Deshmukh(74) *Attorney, Agent, or Firm* — Eric C. Schmalbach(57) **CLAIM**

The ornamental design for a self-closing entry system, as shown and described.

DESCRIPTION

This application contains subject matter related to subject matter contained in co-pending U.S. application Ser. No. 13/570,582 filed on Aug. 9, 2012 and incorporated herein by reference.

FIG. 1 is a perspective view of a self-closing entry system showing my new design;

FIG. 2 is front elevational view thereof;

FIG. 3 is a front elevational view thereof, shown in an alternate position;

FIG. 4 is a top plan view thereof; and,

FIG. 5 is a side elevational view thereof.

The broken lines environment is for illustrative purpose only and forms no part of the claimed design.
